L. P. CROSMAN
PULSE GENERATOR

2,512,851

Filed April 3, 1948

4 Sheets-Sheet 1

Fig. 1.

<img alt="Circuit diagram of a keyboard control system. The diagram shows a flow from a PRELIMINARY PULSE GENERATOR (10, 11, 15) through an UNBALANCED TRIGGER STAGE (12, 13, 14) to a CONTROL SWITCH (15, 16, 17). The CONTROL SWITCH feeds into a MULTI-VIBRATOR (18, 19, 20) and a MIXER FOR 2 1/4 (21, 22, 23). The MULTI-VIBRATOR outputs to a BUFFER STAGES (24, 25, 26) and a FREQUENCY DIVIDER 8 TO 4 (27, 28, 29). The FREQUENCY DIVIDER 8 TO 4 outputs to an INVERTER FOR 6 (30, 31, 32). The INVERTER FOR 6 feeds into a CATHODE FOLLOWER STAGES 4 1/2 (33, 34, 35, 36). The CATHODE FOLLOWER STAGES 4 1/2 outputs to a KEYBOARD (37, 38, 39). The KEYBOARD outputs to a CATHODE FOLLOWER STAGES 1 1/2 (40, 41, 42, 43) and a FREQUENCY DIVIDER 4 TO 2 (44, 45, 46). The FREQUENCY DIVIDER 4 TO 2 outputs to a LIMITER AND GATE (47, 48, 49, 50). The LIMITER AND GATE outputs to an AMPLIFIER FOR 1 (51, 52, 53) and a COUNTER STAGE (54, 55, 56). The COUNTER STAGE outputs to LAMP INDICATORS (57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 299, 300, 301, 302, 303, 304, 305, 306, 307, 308, 309, 309, 310, 311, 312, 313, 314, 315, 316, 317, 318, 319, 319, 320, 321, 322, 323, 324, 325, 326, 327, 328, 329, 329, 330, 331, 332, 333, 334, 335, 336, 337, 338, 339, 339, 340, 341, 342, 343, 344, 345, 346, 347, 348, 349, 349, 350, 351, 352, 353, 354, 355, 356, 357, 358, 359, 359, 360, 361, 362, 363, 364, 365, 366, 367, 368, 369, 369, 370, 371, 372, 373, 374, 375, 376, 377, 378, 379, 379, 380, 381, 382, 383, 384, 385, 386, 387, 388, 389, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 474, 475, 476, 477, 478, 479, 479, 480, 481, 482, 483, 484, 485, 486, 487, 488, 489, 489, 490, 491, 492, 493, 494, 495, 496, 497, 498, 499, 499, 500, 501, 502, 503, 504, 505, 506, 507, 508, 509, 509, 510, 511, 512, 513, 514, 515, 516, 517, 518, 519, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 997, 998, 999, 999, 1000, 1001, 1002, 1003, 1004, 1005, 1006, 1007, 1008, 1008, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1097, 1098, 1099, 1099, 1100, 1101, 1102, 1103, 1104, 1105, 1106, 1107, 1108, 1108, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1196, 1197, 1198, 1198, 1199, 1199, 1200, 1201, 1202, 1203, 1204, 1205, 1206, 1207, 1207, 1208, 1209, 1210, 1211, 1212, 1213, 1214, 1215, 1216, 1217, 1218, 1218, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1258, 1259, 1260, 1261, 1262, 1263, 1264, 1265, 1266, 1267, 1268, 1269, 1269, 1270, 1271, 1272, 1273, 1274, 1275, 1276, 1277, 1278, 1278, 1279, 1280, 1281, 1282, 1283, 1284, 1285, 1286, 1287, 1288, 1289, 1289, 1290, 1291, 1292, 1293, 1294, 1295, 1296, 1296, 1297, 1298, 1298, 1299, 1299, 1300, 1301, 1302, 1303, 1304, 1305, 1306, 1307, 1307, 1308, 1309, 1310, 1311, 1312, 1313, 1314, 1315, 1316, 1317, 1318, 1318, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1358, 1359, 1360, 1361, 1362, 1363, 1364, 1365, 1366, 1367, 1368, 1369, 1369, 1370, 1371, 1372, 1373, 1374, 1375, 1376, 1377, 1378, 1378, 1379, 1380, 1381, 1382, 1383, 1384, 1385, 1386, 1387, 1388, 1389, 1389, 1390, 1391, 1392, 1393, 1394, 1395, 1396, 1396, 1397, 1398, 1398, 1399, 1399, 1400, 1401, 1402, 1403, 1404, 1405, 1406, 1407, 1407, 1408, 1409, 1410, 1411, 1412, 1413, 1414, 1415, 1416, 1417, 1418, 1418, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1458, 1459, 1460, 1461, 1462, 1463, 1464, 1465, 1466, 1467, 1468, 1469, 1469, 1470, 1471, 1472, 1473, 1474, 1475, 1476, 1477, 1478, 1478, 1479, 1480, 1481, 1482, 1483, 1484, 1485, 1486, 1487, 1488, 1489, 1489, 1490, 1491, 1492, 1493, 1494, 1495, 1496, 1496, 1497, 1498, 1498, 1499, 1499, 1500, 1501, 1502, 1503, 1504, 1505, 1506, 1507, 1507, 1508, 1509, 1510, 1511, 1512, 1513, 1514, 1515, 1516, 1517, 1518, 1518, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1558, 1559, 1560, 1561, 1562, 1563, 1564, 1565, 1566, 1567, 1568, 1569, 1569, 1570, 1571, 1572, 1573, 1574, 1575, 1576, 1577, 1578, 1578, 1579, 1580, 1581, 1582, 1583, 1584, 1585, 1586, 1587, 1588, 1589, 1589, 1590, 1591, 1592, 1593, 1594, 1595, 1596, 1596, 1597, 1598, 1598, 1599, 1599, 1600, 1601, 1602, 1603, 1604, 1605, 1606, 1607, 1607, 1608, 1609, 1610, 1611, 1612, 1613, 1614, 1615, 1616, 1617, 1618, 1618, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1658, 1659, 1660, 1661, 1662, 1663, 1664, 1665, 1666, 1667, 1668, 1669, 1669, 1670, 1671, 1672, 1673, 1674, 1675, 1676, 1677, 1678, 1678, 1679, 1680, 1681, 1682, 1683, 1684, 1685, 1686, 1687, 1688, 1689, 1689, 1690, 1691, 1692, 1693, 1694, 1695, 1696, 1696, 1697, 1698, 1698, 1699, 1699, 1700, 1701, 1702, 1703, 1704, 1705, 1706, 1707, 1707, 1708, 1709, 1710, 1711, 1712, 1713, 1714, 1715, 1716, 1717, 1718, 1718, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1758, 1759, 1760, 1761, 1762, 1763, 1764, 1765, 1766, 1767, 1768, 1769, 1769, 1770, 1771, 1772, 1773, 1774, 1775, 1776, 1777, 1778, 1778, 1779, 1780, 1781, 1782, 1783, 1784, 1785, 1786, 1787, 1788, 1789, 1789, 1790, 1791, 1792, 1793, 1794, 1795, 1796, 1796, 1797, 1798, 1798, 1799, 1799, 1800, 1801, 1802, 1803, 1804, 1805, 1806, 1807, 1807, 1808, 1809, 1810, 1811, 1812, 1813, 1814, 1815, 1816, 1817, 1818, 1818, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1858, 1859, 1860, 1861, 1862, 1863, 1864, 1865, 1866, 1867, 1868, 1869, 1869, 1870, 1871, 1872, 1873, 1874, 1875, 1876, 1877, 1878, 1878, 1879, 1880, 1881, 1882, 1883, 1884, 1885, 1886, 1887, 1888, 1889, 1889, 1890, 1891, 1892, 1893, 1894, 1895, 1896, 1896, 1897, 1898, 1898, 1899, 1899, 1900, 1901, 1902, 1903, 1904, 1905, 1906, 1907, 1907, 1908, 1909, 1910, 1911, 1912, 1913, 1914, 1915, 1916, 1917, 1918, 1918, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1958, 1959, 1960, 1961, 1962, 1963, 1964, 1965, 1966, 1967, 1968, 1969, 1969, 1970, 1971, 1972, 1973, 1974, 1975, 1976, 1977, 1978, 1978, 1979, 1980, 1981, 1982, 1983, 1984, 1985, 1986, 1987, 1988, 1989, 1989, 1990, 1991, 1992, PULSE GENERATOR

Loring P. Crosman, Darien, Conn., assignor to
Remington Rand Inc., New York, N. Y., a corporation of Delaware

Application April 3, 1948, Serial No. 18,782

4 Claims. (Cl. 250—27)

1

This invention relates to an electric pulse generator and has particular reference to a controlled multivibrator circuit which will deliver a predetermined number of electrical pulses to an output circuit and then turn itself off. While the invention is subject to a wide range of applications, it is especially suited for use in an electronic calculator and will be described in that application.

As used throughout the specifications and claims, the term "unbalanced trigger" refers to a trigger stage comprising two electronic triodes with circuit components so adjusted that the circuit is stable only when one triode is conducting and the second triode is non-conducting. Applying an actuating pulse to such a stage momentarily switches conductivity and generates a pulse, the duration of which depends upon the circuit constants. This type of circuit is also called a "one-shot multivibrator" and a "flip-flop."

Multivibrator generators have been used in many applications where a square topped electric wave is desirable. In all such applications, including electronic calculating equipment, the multivibrator generates waves continuously as long as the equipment is in operation. Such a system requires accurately timed switching circuits and synchronizing means, especially if the operation depends upon the number of pulses used.

It is an object of this invention, therefore, to provide an improved multivibrator circuit which avoids one or more of the disadvantages and limitations of prior art arrangements.

Another object of the invention is to provide a pulse generator which starts generating electrical pulses as soon as desired and stops after a predetermined number of pulses have been generated.

Another object of the invention is to provide a multivibrator circuit which may be adapted to provide pulses for a system of counting using a radix of five and a radix of two.

Another object of the invention is to provide a pulse generator system which will produce a total of five primary pulses but so arranged that selected pulses may be assigned a double value.

The invention comprises a pulse generator for generating a predetermined number of electrical pulses and includes a multivibrator which is controlled by an electronic switching stage. Two frequency divider stages are included which reduce the number of generated pulses to a single pulse, the output of the second divider stage

2

being coupled back to the switching stage to cut off the generator at the end of the single pulse.

One feature of the invention includes an unbalanced trigger stage which is used to start the multivibrator oscillator. The trigger stage produces a pulse that may be used in conjunction with the multivibrator pulses for counting and controlling other stages.

For a better understanding of the present invention, together with other and further objects thereof, reference is made to the following description taken in connection with the accompanying drawings.

Fig. 1 is a block diagram showing how the various stages are connected.

Fig. 2 is a schematic diagram of connections of part of the pulse system.

Fig. 3 is also a schematic diagram of connections and shows the remaining part of the pulse system.

Fig. 4 is a diagram which indicates how Figs. 2 and 3 are to be combined to show the complete system.

Fig. 5 is a series of graphs showing the character of the pulses produced in various parts of the circuit.

Referring now to Fig. 1 the entire system will be generally described, neglecting at present the detailed features of the invention. A starting key 10 is connected to a preliminary pulse generator 11 which generates a sharp pulse when the key contacts are made. Next an unbalanced trigger stage 12 transforms the sharp pulse into a broad flat-topped pulse of the same magnitude and duration as the pulses which later are generated by the multivibrator. The unbalanced trigger stage 12 also controls an electronic switching stage 13 which turns a multivibrator oscillator 14 on. The switching stage 13 is also operated, but in a reverse direction, by a frequency divider stage 16 to turn the multivibrator off.

The output of the multivibrator, in this example equal to four pulses, is fed to a frequency divider 15 which reduces the four pulses to two (see Fig. 5-e), and these two pulses are fed to a second frequency divider 16 which reduces the number of pulses to one (5-f). The output of this divider 16 is fed back over conductors 17 and 18 to the switching stage, as explained above, and the multivibrator is turned off when the single pulse ends.

During the process, above described, of generating a single starting pulse and four oscillation pulses which are divided into two pulses and a single pulse, there are made available at vari-

ous portions of the circuit, single, double, and quadruple pulse trains which may be used singly or in combination to produce sharp pulse trains to count from one to nine. To this end three buffer stages 20, 21, and 22 are provided, also a mixer stage 23, and an inverter 24.

The pulses which are provided from the above described circuit are indicated graphically in Fig. 5 where voltages are plotted against time. The first pulse, started by the actuation of key 10, and transferred by conductor 25, is shown graphically by a sharp negative pulse 26 which occurs at the start of the operation cycle. The output of the unbalanced trigger stage 12 is flat-topped pulse 27 which is tapped by a buffer cathode follower stage 21 and delivered to a keyboard switching assembly 28. The output of the control switching stage 13 is shown in Fig. 5-c as a long flat-topped wave 30 which must attain its maximum value before the multivibrator 14 can function.

The graph of the multivibrator pulses 31-d shows the square-topped waves usually produced by such a circuit. The waves 32 and 33 (Fig. 5, e and f) produced by the two frequency divider circuits are shown in their time relation to the starting pulses, indicating that the voltage fall in the applied wave is the controlling action which switches conduction in each divider stage.

Referring again to Fig. 1, the keyboard 28 contains ten manually settable switches which designate and control the number and value of the pulses transmitted to an output circuit. If the number to be transmitted is even, the pulses are delivered to the left-hand side of amplifier stage 34 (Fig. 3) and transmitted to the even-designated stages in counter 35 without causing any other pulse. If the number to be transmitted is one, the keyboard switch delivers the pulse to the right-hand side of stage 34 where it is amplified and sent to counter stage A-1. If the number to be transmitted is odd and greater than one, a single pulse is sent to the right-hand side of stage 34 while the remaining pulses, representing an even value, are sent through the left-hand side of stage 34 to stages 35. The counter then may be considered to be composed of two parts, an even-odd stage and a series of five even stages.

The output of the counter stages 35 may be used by any suitable calculator circuit, storage device, or read-out mechanism. In order to simplify the circuit, the present system is shown operating a bank of ten lamp indicators 37.

Having now described the general system of pulse generation, reference is made to Figs. 2 and 3 where the detailed schematic wiring diagram is shown. The preliminary pulse generator circuit 11 includes a vacuum tube 40, a neon gas tube 41 connected between the anode and control electrode circuit, and a starting key 10 which is shunted around a condenser 42 connected between the cathode and control electrode circuits. The unbalanced trigger circuit 12 is adjusted to conduct on the left side, as indicated in Fig. 2 by cross hatched lines on electronic double triode 43. Conductor 25 connects the anode of tube 40 with the control electrode circuit of tube 43 and transmits the preliminary pulse to shift conductance in the trigger stage. The output pulse generated by the trigger stage 12 is transmitted over conductor 45 to the stabilized trigger stage 13 containing tube 47, used in this circuit as a switch. Another output circuit is run directly from the anode of tube 43 and is transmitted over conductor 39 to the left-hand side of buffer

amplifier 21. Conductor 45 is connected to the left-hand control electrode 46 (through a blocking condenser) and can only turn the switch to the "on" position. Another circuit, to be described later, must be used to turn to the "off" position.

The switching stage 13 controls the multivibrator 14 by conductor 48 which connects the left-hand anode of tube 47 to the right-hand control electrode circuit of the multivibrator tube 50 to control the potential of that electrode. The multivibrator stage 14 is similar to prior art multivibrators which have been described in technical articles and books. In this oscillator only the left-hand anode circuit is tapped to produce positive pulses, the negative pulses being neglected. The multivibrator output is transmitted over conductors 51 and 52 to frequency divider 15 and buffer amplifier 20.

Frequency divider 15 comprises a double triode 53 with associated circuits which make it a stabilized trigger. The input conductor 51 to this tube is connected to both control electrodes through condensers so that each pulse received by the circuit transfers conductance from the side that has been in a conductive state to the other side. To describe such a conductance transfer in this type of circuit the term "actuate" will be used hereinafter. It should be obvious that with any even number of pulses applied, such as four, the left-hand anode will pass through the conductive state twice or one half the number of pulses applied. The divided pulses 32 as shown in Fig. 5-e have a wave form similar to the original pulses, but the time intervals for maximum and zero voltage duration are twice as long.

The output of frequency divider stage 15 is transmitted by conductors 54 and 55 to frequency divider stage 16 and buffer amplifier 22. The frequency divider stage 16 is exactly the same as stage 15 and divides the two pulses, producing a single pulse (see curve Fig. 5-f). The output of this stage is taken from the left anode circuit of tube 56 and is transmitted by conductors 17 and 18 to the right-hand side of buffer stage 21 and the right-hand control electrode of tube 47. The latter connection is utilized to turn off the multivibrator.

Stage 21 is a double buffer amplifier whose left-hand elements amplify the single pulse generated by the unbalanced trigger stage 12 and the right-hand elements amplify the single pulse from stage 16 as described above. Tube 60 in stage 21 is normally conducting and acts as an amplifier in the usual sense. The output circuits from both halves are taken across cathode resistors 61 and 62 and transmitted over conductors 63 and 64 to the keyboard 28 where the pulses may or may not be transmitted depending upon the closure of the numbered switches.

From the keyboard two conductors 65 and 66 connect to a limiter stage 34. The limiter stage is normally adjusted with its control electrodes below the conducting point so that only positive pulses will cause conduction in the anode circuit. A negative pulse will have no effect on the tube conductivity. The left-hand side of stage 34 receives a pulse whenever an even designated key is depressed, the right-hand side is pulsed whenever the "one" key is depressed, and both sides are pulsed whenever the 3, 5, 7, or 9 keys are depressed.

The odd or right-hand section of stage 34 has its output connected to trigger stage A-1 which is

normally conducting on the left-hand side. A positive pulse transmitted over conductor 66 produces a negative pulse in anode conductor 67 and actuates stage A-4, transferring the conducting path within the tube to the right-hand side. This lowers the potential of conductors 68 and 70 and delivers a negative pulse to the control electrode of tube 71 in an amplifier stage 72. Stage 71 acts as a buffer amplifier and inverter, the anode being connected directly to conductor 73 which in turn is connected to all the right-hand control electrodes of a series of five trigger stages. These five stages represent the even numbered digits in the decimal system and are designated A-0, A-2, A-4, A-6, and A-8 to indicate the values handled by them. The A-0 stage has part of its output connected to the left-hand control electrode of the A-2 stage; the output of the A-2 stage is connected to the left-hand control electrode of the A-4 stage; the A-4 and A-6 stages being similarly connected, and the A-8 stage output connected back to the control electrode of the A-0 stage.

Each of the five stages, A-0 to A-8, inclusive, has the output of its left-hand section connected to one terminal of two neon indicator lamps in the indicator bank 37. The other terminals of the lamps are connected by conductors 74 and 75 to rectifying elements 76 and 77 and then to the two anodes in stage A-1.

A zeroize or normalizing key 78 is included in series with one of the cathode conductors 80 so that its opening will insert a resistance in series with all the cathodes that normally should be non-conducting.

Operation

In order to describe the operation, let it first be assumed that the circuit is in its normal or quiescent state. Counter stages A-1, A-2, A-4, A-6, and A-8 are all conducting on the left-hand side and A-0 is conducting on the right. Neon indicator lamp 79 is burning because one of its conductors 81 leads to the anode in stage A-0 which is at high potential and the other conductor 74 leads through rectifier 76 to the anode of stage A-1 which is at low potential.

Now assume that the number 4 key in the keyboard 28 be depressed, joining conductor 65 with conductor 81. Then the start key 10 is closed and condenser 42 is slowly discharged thereby providing voltage for the ionization of neon tube 41 and impressing a sharp positive pulse on the control electrode of tube 40. The results of this pulse are transmitted over conductor 25 to the unbalanced trigger stage 12 which produces a flat-topped wave (Fig. 5-b) which is transmitted over conductors 39 and 45 to the control electrode 46 of switching stage 13 and the buffer amplifier stage 21.

The application of a pulse to control electrode 46 of tube 47 turns on the multivibrator by increasing the potential on control electrode 83 to a value that permits oscillation. The output of the multivibrator is transmitted over conductor 51 to the first frequency divider stage 15, at which point an output pulse is transmitted over conductors 54 and 55 to the buffer amplifier in stage 22. The output of this stage consists of a double pulse shown in Fig. 5-e and is transmitted by conductor 81 to key contacts 84 under the number 4 key. Then over conductor 65 to the left-hand side of amplifier stage 34 which normally is biased to the cut-off point. The output of 75

stage 34 is transmitted over conductor 73 as two sharp negative pulses shown in Fig. 5-k. The pulses are sharpened by the capacitor input and are made negative by the anode output circuit.

5 The two pulses are applied to the right-hand control electrode of all the even counter stages, A-0, A-2, A-4, A-6, and A-8. The first negative pulse 85 actuates only the A-0 stage since it is the only stage conducting on the right-hand side. The application of the pulse changes the conduction to the left-hand side and in making the transfer a negative pulse is sent over conductor 86 to the A-2 stage and transfers its conductance to the right-hand side.

10 15 When the second negative pulse 87 from stage 34 arrives at the counter stages 35 the A-0 stage is conducting on the left and the A-2 is conducting on the right, hence only the A-2 stage will be affected. Its conductance will be transferred to the left and in doing so it will cause the actuation of the A-4 stage. Hence at the end of the double negative pulse only the A-4 stage is conducting on the right. This condition causes the number 4 neon indicator lamp to light since one of its conductors 90 leads to the left-hand anode of stage A-4 which now is at high potential while the other conductor 14 leads to the left-hand anode of stage A-1 which is at low potential.

20 25 The above described action is finished a small interval of time before the end of a pulsing cycle since the second activating pulse 87 occurs at time t_7 as shown on Fig. 5-k. The multivibrator continues with its fourth pulse and is finally turned off by the action of the second frequency divider

30 35 stage 16 which sends a pulse at time t_9 over conductor 17 to the right-hand control electrode of tube 47 in stage 13 which reduces the potential on conductor 48 and stops the multivibrator action.

40 45 After the finish of the pulsing cycle the counter stages 35 and the indicator lamps remain in their operated condition so that they may be ready for additional pulses or until the result may be copied or transferred to another part of the calculator system. When it is desired to normalize the system and return the counter stage to zero condition the switch 78 is opened.

50 55 When this is done, a resistance 91 is placed in series with conductor 80 which connects with all the cathodes that are non-conducting when the device reads zero. If the cathodes are in a conducting condition the added resistance causes a potential drop in the cathode supply line which reduces the potential difference between the cathode and the control electrode to a value where the anode current is completely cut off. The same action increases the voltage of the control electrode in the non-conducting half of the stage until it reaches the conducting state.

60 65 In order to illustrate the action of the A-1 stage, let it be assumed that, starting from the quiescent state, the nine key in the keyboard 28 is depressed. Then, when the start key 10 is closed, the preliminary pulse from stage 11 actuates the unbalanced trigger stage 12 and produces the first flat-topped wave shown in Fig. 5-b. The output of trigger stage 12 is transmitted to the switching stage 13 as before, but 70 another output conductor 39 transmits the pulse to buffer amplifier stage 21 and thence from cathode resistor 61 over conductor 63 to one of the contacts 93 in the nine key assembly. The pulse which is transmitted through these contacts starts at time t_1 and stops at time t_2 (see

Fig. 5-b) and is in advance of the multivibrator pulses.

The multivibrator output to the nine key may be traced from the multivibrator stage over conductors 51 and 52 to the buffer amplifier stage 20, thence over conductor 94 to the bottom contacts 95 of the nine key.

The top contacts 93 of the nine key connect conductor 63 with conductor 66 which connects to the right-hand side of the amplifier tube in stage 34. Contacts 95 connect conductor 94 with conductor 65 which connects to the left-hand side of the same tube. Thus both sides of stage 34 receive pulses, on the right a single pulse 27 (Fig. 5-b) and on the left four pulses 31 (Fig. 5-d). The pulses are applied to the control electrode through small condensers, hence the anode currents have wave forms as indicated in Fig. 5-m and 5-i. The pulse applied by conductor 66 is amplified and transmitted over conductor 67 to the A-1 stage which is thereby actuated and made to conduct on the right.

The four negative pulses transmitted from stage 34 over conductor 73 are all applied to the right-hand control electrodes of all five tubes in the counter stage 35. The first stage A-0 is the only stage affected by the first pulse since it is the only stage in this group conducting on the right. When actuated, it transfers its conductance to the left, and in doing so sends a pulse to the next stage A-2 which actuates it and changes its conductance to the right. When the second of the train of four pulses arrives only the second stage is affected because now it is the only stage conducting on the right. It changes to the left and as before actuates the next higher stage. This process continues until the last pulse actuates stage A-6, transfers its conductance to the left, and actuates the A-8 stage by transmitting a pulse over conductor 98. Therefore, at the end of the pulsing cycle stages A-1 and A-8 are conducting on the right. Under these conditions, number nine neon lamp will be lighted because its upper conductor 97 leads to the high potential point in stage A-8 and its lower conductor 75 leads, through rectifier 77, over conductor 68 to the low potential point in stage A-1.

Having now described the generation and recording of values of four and nine it will be obvious how the other values are recorded. All even valued numbers are recorded by transmitting a number of pulses to the even numbered ring; the number of pulses being equal to half the number to be recorded. All odd numbers are recorded by actuation of the A-1 stage and the recording of the even number one less than the desired odd number.

Actuating pulses for recording two and four are illustrated in Figs. 5-l and 5-k by single and double negative pulses and are obtained from frequency divider stages 16 and 15. Actuating pulses for recording eight are shown in Fig. 5-i and are obtained directly from the multivibrator output. Actuating pulses for recording six are shown in Fig. 5-j and are obtained from mixer stage 23 by the addition of a single and a double pulse. An inverter stage 24 (Fig. 5-h) and a buffer amplifier are employed to obtain the proper segregation and polarity.

From the above description it will be evident that the invention may be employed to furnish electric pulses to electronic calculator systems for recording and adding predetermined values.

While there have been described and illus- 75

trated, specific embodiments of the invention, it will be obvious that various changes and modifications may be made therein without departing from the field of the invention which should be limited only by the scope of the appended claims.

What is claimed is:

1. A pulse generator for generating a plurality of electrical pulse trains, each having a predetermined number of electrical pulses comprising, a multivibrator for producing electrical oscillations, an electronic switching stage under control of a manually operated switch for starting the multivibrator, a plurality of frequency divider stages coupled to the multivibrator for producing said plurality of pulse trains which include a single pulse, and coupling means between said frequency divider stages and the electronic switching stage for turning off the multivibrator when the single pulse ends.

2. A pulse generator for generating a plurality of electrical pulse trains, each having a predetermined number of electrical pulses comprising, a multivibrator for producing electrical oscillations, an electronic switching stage for starting the multivibrator, an unbalanced trigger stage coupled to the switching stage for generating a single pulse when actuated, a manually operated switch for causing the actuation of said trigger stage, a plurality of frequency divider stages coupled to the multivibrator for producing said plurality of pulse trains which include a single pulse, and coupling means between said frequency divider stages and the electronic switching stage for turning off the multivibrator when the single pulse ends.

3. A pulse generator for generating a plurality of electrical pulse trains, each having a predetermined number of electrical pulses comprising, a multivibrator for producing electrical oscillations, an electronic switching stage for starting and stopping the multivibrator, an unbalanced trigger stage coupled to the switching stage for generating a single pulse in advance of the multivibrator oscillations and for controlling the switching stage to start the multivibrator when the single pulse from the trigger stage ends, a manually operated switch for causing the actuation of said trigger stage, a plurality of frequency divider stages coupled to the multivibrator for producing said plurality of pulse trains which include a single pulse from one of the frequency dividers, and coupling means between said frequency divider stages and the electronic switching stage for turning off the multivibrator when the single pulse from one of the frequency dividers ends.

4. A pulse generator for generating a plurality of electrical pulse trains, each having a predetermined number of electrical pulses comprising, a multivibrator for producing electrical oscillations, an electronic switching stage for starting and stopping the multivibrator, an unbalanced trigger stage coupled to the switching stage for generating a single pulse in advance of the multivibrator oscillations and for controlling the switching stage to start the multivibrator when the single pulse from the trigger stage ends, means for actuating said trigger stage, a plurality of frequency divider stages coupled to the multivibrator for producing said plurality of pulse trains which include a single pulse from one of said divider stages, coupling means between the divider stages and the switching stage for turning off the multivibrator when the single pulse

from one of the divider stages ends, and connecting means from two or more frequency divider stages through a mixer stage to a utilization circuit to obtain a number of pulses not an integral sub-multiple of the number delivered by the multivibrator. 5
